PNEUMATIC CYCLE TIMER

Peter R. Brock, Hagerstown, Md., and Alexander v. d. Luft and William F. Schmauss, Martinsburg, W. Va., assignors to E. I. du Pont de Nemours & Company, Wilmington, Del., a corporation of Delaware

Application September 13, 1954, Serial No. 455,452

4 Claims. (Cl. 137—102)

This invention relates to an automatic cycle timing apparatus, and particularly to a widely adjustable, continuously operable pneumatic cycle timer.

It is frequently necessary in industrial manufacturing to control simultaneously the performance of paired repetitive operations by the use of cycle timers, the most common types of which are spring-actuated or electrical clock devices. Spring-actuated apparatus requires periodic winding, which is disadvantageous, and apparatus employing electrical energy as the power source is objectionable from the standpoint of fire or explosion hazards.

An object of this invention is to provide a continuously operable pneumatic cycle timer for the coordination of at least one pair of time-related repetitive operations which is widely adjustable to permit precise time regulation of one operation of the pair with respect to the other, which is regulable over a relatively wide range of cycle time intervals and which may be readily adjusted during operation.

Another object of this invention is to provide a cycle timer which is completely pneumatic and which is thus free from inherent fire and explosion hazards.

Another object of this invention is to provide a pneumatic cycle timer which is simple in construction and maintenance, low in cost, reliable in operation and which is adapted to use in any manufacturing building provided with air pressure service facilities.

The manner in which these and other objects of this invention are accomplished will be apparent from the detailed description and the following drawings, in which:

Fig. 1 is a representation of a preferred embodiment of timer according to this invention adapted to the control of a single pair of repetitive operations, all apparatus components except the interconnecting tubing being shown in section to facilitate understanding of the functioning of each, and

Fig. 2 is a time-pressure diagram comprising plots of the output signal characteristics of the apparatus of Fig. 1 (B and C) drawn to the same scale, but with origins displaced along the ordinate axis as indicated, together with a plot (A) of the pressure existing in chamber 108 of reservoir 105, drawn to a different ordinate scale than the output signal plots and from yet a different origin, as indicated, but all three plots having a common time abscissa axis.

Referring to Fig. 1, air is supplied to the apparatus through line 10 connected with the usual building air supply; not shown, it being assumed, of course, that a conventional pressure regulator is provided so that a substantially constant air pressure at the supply source is always preserved, and at a suitable level for operation of the control devices hereinafter described. Line 10 is connected into the inlet side of reverse-acting amplifying relay 11 and is provided with two open branch lines 12 and 13. Line 13 opens into the inlet side of direct-acting amplifying relay 14, while line 12 is con-

2

nected to the inlet side of valve 17 of cycling relay 18, which is of the snap-acting type.

Reverse-acting amplifying relay 11 may be a model 67-100R manufactured by Moore Products Co., which comprises housing 22, provided with a pressure-equalizing vent 23 opening to the atmosphere, within which is mounted the conventional double-bellows actuator, indicated generally at 24, for the valving member of the device. Spring 25, biasing the valving member of relay 11 towards open position with respect to air flow through the relay from line 10, permits adjustment of the set point of the device within a wide range of preselected values by regulating thumb screw 26 supporting the end of the spring opposite the bellows.

15 The valving member of relay 11 comprises ball members 27 and 28 integral with a common valve stem 29, the upper end of the stem being integral with a plate 30 fixedly attached to the upper ends of the two bellows of actuator 24 and thus constituting a bearing surface for spring 25. Plate 30 is shown in section, as is the upper end of valve stem 29, to more clearly show the exhaust opening from the interior of the inner bellows of actuator 24 to the interior of housing 22 and thence to the atmosphere through vent 23, this passage comprising lateral ports 31 and axial passage 32. With this construction it will be understood that valve stem 29 rises and falls in a vertical plane as bellows actuator 24 expands or contracts axially with, respectively, rise or fall in pressure applied to its annular interior.

30 Relay 11 is provided with a double valve seat 33, against the upper side of which ball 27 abuts when the pressure within the interior of actuator 24 is insufficient to overcome the biasing action of spring 25, during which time ball 28 is out of contact with the lower side of the seat. When the pressure within actuator 24 reaches a level such that spring 25 is compressed, which is the condition in which the apparatus is shown in Fig. 1, valve stem 29 moves upwardly, thus bringing ball 28 into contact with the lower side of seat 33 and simultaneously lifting ball 27 from seated position. Valve stem 29 is provided with an integral cylindrical guide portion 34 which fits within the central passage 35 of seat 33 with sufficient clearance so that the flow of air through the passage is not substantially impeded, and a connecting passage 36 is provided in the housing body in open communication with passage 35. Signal line 37 is connected to the other end of passage 36. As is customary in pneumatic relay construction, the lower end of valve stem 29 is extended to form a guide portion which is co-axial with the open end of line 10 and of a reduced diameter such that it does not impede free passage of air past it, and plug 38 is provided with upraised projections 39 which serve as retaining lugs for the lower end of valve-biasing spring 40 which abuts ball 28 and thus insures positive valving action at all times. It might be mentioned that flow of air through relay 11 is regulated exclusively by the positions of balls 27 and 28 with respect to valve seat 33 and that the construction of the apparatus is such that there is free service air flow from line 10 through the relay to line 37 whenever ball 28 is moved away from contact with the lower side of seat 33. Relay 11 is further provided with a passage 44 opening into the annular interspace of actuator 24 and connected with line 45, which is hereinafter described in detail.

45 Direct-acting amplifying relay 14 may be a model 67 manufactured by the Moore Products Co., which is similar in construction to relay 11 in that it is provided with a housing 46, a housing vent 47, a double bellows actuator 48, an actuator-biasing spring 49 and a spring tension adjusting thumb screw 50. This relay is provided with a valving member comprising ball 51 integral with valve stem 52 which is secured at the upper end to plate

50

55

60

65

70

53 in the same manner as described for relay 11 and is also provided with inner bellows venting means consisting of lateral ports 54 and axial passage 55. The valving arrangement for relay 14 differs from that of relay 11 in that a valve seat is provided for ball 51 at both extremes of travel of valve stem 52, the upper seat 56 being integral with the base of housing 46 while the lower seat consists of a continuous ring 57 integral with centrally drilled plug 58. The recess 59 in which ball 51 moves communicates with a passage 60 in the housing base which, in turn, communicates with the other signal line 61 through which control is to be exercised, all as hereinafter described in detail. Thus, when bellows actuator 48 is expanded axially under interior pressure, which is the condition represented in Fig. 1, ball 51 clears valve seat 57, closing against valve seat 56, thereby permitting free flow of service air from line 13 through the relay to signal line 61. Conversely, when the pressure in the interior of actuator 48 decreases, permitting spring 49 to collapse the double bellows, ball 51 clears seat 56 and abuts seat 57, thereby relieving the pressure in line 61 by escape of air around the upper part of valve stem 52 and thence to the atmosphere through ports 54, passage 55 and vent 47. Relay 14 is provided with a biasing spring 62, insuring positive valve action, and a passage 63 connecting with line 64, which supplies air to actuator 48 as hereinafter described.

Snap-acting relay 18 may be a model RO49A2 manufactured by the Minneapolis-Honeywell Co., which comprises housing 69 provided with a pair of spring-biased valves, of which one, i.e., 17, has been hereinabove mentioned, while the other is indicated at 70. Threaded valve stop plugs 71 provided with integral depending skirt portions 72 engage with the tapped upper ends of the openings constituting the valve chambers in the head of housing 69 and limit the upper displacement of the valves in the chambers, while the lower ends of the chambers are provided with valve seats 73, for valve 17, and 74, for valve 70, against which the respective valves close at the lower extremes of travel. The lower ends of the stems of valves 17 and 70 abut the neoprene diaphragm 77, which is attached by mounting plates 78 to the underside of the head of housing 69 in air-tight relationship and defines therewith chamber 79, which is in open communication with the sides of valve seats 73 and 74 opposite the associated valves and also with passage 80 connected to line 81. The lowermost mounting plate 78 is provided with a flange 82 which carries rocking lever 83 pivoted at 84, the two ends of the lever being provided with screw deflectors 85 and 89 bearing at the ends against diaphragm 77 on the side opposite that abutting the valve stems of 17 and 70.

The lower part of housing 69 is provided with a chamber 90 closed off by diaphragm 91 to which is secured the end of rod 92, rod 92 being slidably supported for movement lengthwise of the housing on ways 93, only one of which is shown, attached to the base of the housing. The opposite end of rod 92 is biased in opposition to diaphragm 91 by spring 94, adjustable in compression by thumbscrew 95. Yoke 96 is fixedly secured to rod 92 and is bifurcated at the lower end, so that the two legs rest on the outside surfaces of ways 93 and retain rod 92 in position thereon. The upper end of yoke 96 is attached to one end of coiled spring 97, the opposite end of which is secured by a pivot connection, not detailed, to tongue 98 integral with lever 83. Spring 97 pivots lever 83 in a counterclockwise direction, thus permitting valve 17 to close under the action of its biasing spring, when rod 92 is deflected to right-hand position by the highest pressure, applied through diaphragm 91, attained in chamber 108 of reservoir 105, hereinafter described, and pivots lever 83 in a clockwise direction, thereby opening valve 17 and permitting valve 70 to close, under the lowest pressure attained in chamber 108. Housing 69 is provided with a vent 99, connecting the chamber of valve 70 to atmosphere, and a passage 100 connected

to line 101, which in turn is in open communication with passage 106 of reservoir 105 and with line 45.

Reservoir 105 comprises an air-tight vessel provided with an entrance chamber 107 and a pressure build-up chamber 108, the two chambers being connected through a throttling valve 109, the setting of which is adjustable by thumbscrew 110 to obtain a wide range of preselected rates of air flow through the valve. Air is supplied to the reservoir via line 81 hereinbefore described, which is connected to inlet passage 111 of entrance chamber 107.

Referring to Fig. 2, the operation of the embodiment described is best understood by consideration of the pressure-time relationships existing as regards chamber 108 of reservoir 105, and the corresponding relationships resulting therefrom as regards signal lines 37 and 61.

It should be pointed out that the pressure-time relationships depicted in Fig. 2 are represented with reference to a common time axis as abscissa but, to avoid confusing overlying of the pressure plots, each has been referred to a separate origin on the ordinate scale, the pressure scales for each of the two signal line pressures being of equal magnitude, whereas the pressure scale for chamber 108 is magnified, all in the interests of facilitating an understanding of operation.

With atmospheric pressure existing in line 10, valve 17 of relay 18 will initially be open and valve 70 will be closed, responsive to its biasing spring, whereas ball member 28 of reverse-acting relay 11 will be clear of valve seat 33 thereby permitting instantaneous full line pressure build up in signal line 37, as represented by plot C. Accordingly, relay 11 will be in "on" position, with ball member 27 closed against valve seat 33 under the influence of spring 25.

At the same time, ball member 51 of direct-acting relay 14 is closed on valve seat 57 under the action of spring 49, thereby preventing passage of air through relay 14 to signal line 61, as indicated by plot B, and relay 14 will be in "off" position considered with reference to the cycle this relay controls. As superatmospheric pressure is applied to line 10, the pressure in chamber 108 will build up substantially linearly, as indicated in plot A of Fig. 2, by passage of air past open valve 17, through chamber 79, passage 80, line 81, passage 111, chamber 107, and throttling valve 109, the rate of pressure build up being determined by the setting of the latter valve.

Since chamber 108 is in open communication with bellows actuators 24 and 48 through lines 101, 45 and branch line 64, these actuators are biased against their associated springs and, when the set point pressures of each are in turn attained, the actuators reverse the positions of the associated valving members and reverse the conditions of the relays from those originally existing. Thus, as seen in plot A relay 14 remains in "off" condition until the pressure in chamber 108 attains level d , when relay 14 opens and permits the pressure in line 61 (refer plot B) to rise practically instantaneously from atmospheric level to the full line pressure carried in signal line 10.

As the pressure in chamber 108 continues to increase, the set point pressure level of relay 11 is finally attained at point e , plot A, whereupon bellows actuator 24 closes ball member 28 on seat 33, at the same time lifting ball member 27 to open position, thus permitting exhausting from line 37 back through passages 36 and 35, the inner bellows of the actuator and thence to the atmosphere through ports 31, passage 32 and vent 23. Relay 11 thus reverts to "off" condition as indicated by the first downward step of plot C.

The pressure in chamber 108 continues rising to the level x of plot A when diaphragm 91, responding to the pressure built up in chamber 90, pushes rod 92 to the right and thus triggers spring 97 to snap lever 83 in a counter-clockwise direction permitting valve 17 to close and opening valve 70. Fig. 1 represents the apparatus at this instant of operation. Back flow is thereby permitted from chamber 108 and bellows actuators 24 and 48 past

needle valve 109 and through chamber 107, line 81, and chamber 79 with discharge to the atmosphere through vent 99. At point *f* of plot A the set point of relay 11 is again attained and this relay shifts to "on" position again with the pressure in signal line 37 at once rising, as indicated in plot C. With further pressure drop in chamber 108 and bellows actuator 48 to point *g* of plot A, relay 14 reverts to "off" position, as indicated in plot B. Finally, the pressure in chamber 108 reaches level *y*, at which point snap-acting relay 18 functions under the biasing force of spring 94 to shift rod 92 to the left, thereby causing lever 83 to tilt in a clockwise sense, closing valve 70 and opening valve 17. The cycle hereinabove described then repeats continuously with variation of pressure according to the sawtooth pattern of plot A as long as operating air is supplied to the apparatus through line 10.

It will be apparent that the cycle times for each of the amplifying relays and also for the snap-acting relay are independently adjustable over very wide ranges. It will be understood that the signal lines are provided with conventional pneumatic devices, known to those skilled in the art, which are responsive to the pressures carried in these lines and thereby controlled by the apparatus of this invention. While only one pair of signal lines has been described, it is clear that more than one such line may be connected to one or both of the two relays to synchronize a multiplicity of operations or, of course, several pairs of relays may be employed with one reservoir to preserve independent control for each pair of signal lines involved, provided that the time characteristic for the reservoir meets the requirements of the situation which it is desired to control.

The embodiment hereinabove described in detail makes possible the achievement of certain especially desirable operating conditions as regards the downstream control instruments in circuit with the signal lines and therefore the construction described is preferred. However, it will be particularly understood that the pneumatic relays need not be employed in direct- and reverse-acting pairs but that, instead, pairs, or greater groupings, of either direct-acting or reverse-acting relays can be utilized. With paired relays of the same types overlapping operation of each relay with respect to its paired relay is still attainable in similar manner to that represented in Fig. 2, except that both relays will then arrive at the same condition in each phase of pressure variation in the reservoir, as distinguished from opposite phase operation for the preferred embodiment. Thus, with direct-acting relays paired, both will go "on" with pressure rise in chamber 108, and "off" with pressure drop therein, while paired reverse-acting relays function oppositely, going "on" with fall in pressure and "off" with rise in pressure. It will be further understood that yet other relays may be utilized in series or in series-parallel relationship with the main control relays hereinabove described to obtain a variety of desirable control patterns suited to the requirements of the process or operation which it is desired to control, but such modifications are not described in further detail as they do not relate to this invention.

From the foregoing it will be understood that this invention is capable of relatively wide modification by those skilled in the art without departure from its essential spirit, wherefore it is intended to be limited only by the scope of the following claims:

What is claimed is:

1. A pneumatic cycle timer comprising in combination a gas pressure source, at least one pair of pneumatic relays each having service gas inlets in communication with said gas pressure source and service gas outlets each in communication with at least one individual signal line, a cycling relay having a chamber provided with a valved port in communication with said gas pressure source and a second valved port venting to atmosphere, said cycling relay being further provided with gas pressure-actuated means for opening and closing said valved ports in alternation upon the application of preselected pressures to said pressure-actuated means, a gas storage reservoir provided with two gas storage chambers, a throttling valve connecting said two gas storage chambers, gas passage means connecting said chamber in said cycling relay with one of said gas storage chambers, and other gas passage means connecting the other of said gas storage chambers in operative relationship with said pressure-actuated means and with the actuating means of said pneumatic relays.

2. A pneumatic cycle timer according to claim 1 wherein said pneumatic relays are of the double bellows-actuated type.

3. A pneumatic cycle timer according to claim 1 wherein said throttling valve comprises a needle valve.

4. A pneumatic cycle timer comprising in combination a gas pressure source, at least one direct-acting pneumatic relay and at least one reverse-acting pneumatic relay having service gas inlets in communication with said gas pressure source and service gas outlets each in communication with at least one individual signal line, a cycling relay having a chamber provided with a valved port in communication with said gas pressure source and a second valved port venting to atmosphere, said cycling relay being further provided with gas pressure-actuated means for opening and closing said valved ports in alternation upon the application of preselected pressures to said pressure-actuated means, a gas storage reservoir provided with two gas storage chambers, a throttling valve connecting said two gas storage chambers, gas passage means connecting said chamber in said cycling relay with one of said gas storage chambers, and other gas passage means connecting the other of said gas storage chambers in operative relationship with said pressure-actuated means and with the actuating means of said direct-acting and reverse-acting pneumatic relays.
